WINDOW REGULATOR MECHANISM

Theodore H. Johnstone, Lincoln Park, and Wilford B. Shrode, Huntington Woods, Mich., assignors to General Motors Corporation, Detroit, Mich., a corporation of Delaware

Filed Feb. 18, 1960, Ser. No. 9,483
5 Claims. (Cl. 296—44)

This invention relates to window regulator mechanisms and more particularly to a combined vehicle window regulator mechanism and latching means.

The window regulator mechanism and latching means of this invention is primarily intended for use with vehicle ventilation windows which are swingable about a vertically disposed axis between opened and closed positions. It is desirable that a latch be provided to latch the window in closed position and prevent forcible entry into the body. In the past, a manual latch has often been provided to latch the window either to the door or to the division post channel in the closed position thereof. Such latches have the disadvantage of requiring the operator to perform two separate functions, one being that of moving the window between open and closed positions, and the other being that of latching and unlatching the window. Very often the operator may forget to latch the window in the closed position thereof or may forget to unlatch the window prior to trying to move the window to an open position.

The regulator mechanism and latching means of this invention automatically latches the window to the body when the window has been moved to closed position, and automatically unlatches the window from the body upon initial movement toward an open position. The latching and unlatching of the window is automatically accomplished whereby the operator need only turn the usual manual crank or operate the power-operated mechanism in order to perform both the latching and unlatching function and the function of moving the window between its open and closed positions. Thus, the regulator mechanism and latching means of this invention has several distinct and unique advantages over the usual manual latch.

The primary object of this invention is to provide an improved combined window regulator mechanism and latching means for vehicle windows. Another object of this invention is to provide an improved combined window regulator mechanism and latching means for vehicle windows which is operative to automatically latch the window to the body when moved to the closed position thereof, and to automatically unlatch the window from the body upon initial movement thereof to an open position. A further object of this invention is to provide an improved combined window regulator mechanism and latching means for vehicle windows which includes a single control means operative to both move the window between its opened and closed positions and to latch the window to the body upon movement of the window to closed position and unlatch the window from the body upon initial movement thereof toward an open position. Yet, a further object of this invention is to provide an improved latching means for a movable vehicle window which is operative to latch the window in the closed position thereof, and unlatch the window upon initial movement thereof toward an open position.

These and other objects of this invention will be more readily apparent from the following specification and drawings wherein:

FIGURE 1 is a side elevational view of a portion of a vehicle body having a swingable ventilator window and embodying a combined window regulator mechanism and latching means according to this invention;

2

FIGURE 2 is an enlarged partially broken away sectional view taken generally along the plane indicated by line 2—2 of FIGURE 6;

FIGURE 3 is an enlarged view taken generally along the plane indicated by line 3—3 of FIGURE 6;

FIGURE 4 is an enlarged sectional view taken generally along the plane indicated by line 4—4 of FIGURE 6, and showing the window in a closed and latched position;

10 FIGURE 5 is a view similar to FIGURE 4 showing the window in an unlatched and partially open position;

FIGURE 6 is an enlarged partially broken away view of a portion of FIGURE 1, and

15 FIGURE 7 is a view of a portion of FIGURE 6 showing the ventilator window in an unlatched and partially open position.

Referring now to the drawings, a vehicle body 10 includes a windshield 12, a roof 14, and a front door 16, the upper edge portion 18 of which is spaced from the roof header 20 to define therewith a window opening 22. Mounted on door 16 is a generally triangularly-shaped ventilator window frame 24 which mounts a swingable ventilator window 26 for opening and closing the forward portion of window opening 22. The rear portion of the window opening 22 is opened and closed by a conventional vertically movable door window 27, indicated schematically in FIGURES 4 and 5. A combined window regulator mechanism and latching means 28 according to this invention is provided for window 26 in order to move the window between its opened and closed positions, and to additionally automatically latch the window in its closed position and to unlatch the window upon initial opening movement thereof. This regulator mechanism and latching means will now be described with reference to FIGURES 2 through 6 of the drawings.

As best shown in FIGURES 2 and 6, frame 24 includes a depending integral flange 30 which is bolted at 32 to the inner panel of door 16 in order to fixedly mount the frame on the door. A combined clutch and reduction gear drive unit 34 is bolted at 36 to flange 30. The gear drive unit includes a manual operating handle 38, FIGURE 1, for the operator and an output driven shaft 40 provided with a slot 42. Slot 42 receives the lower flattened end of the lower window pivot shaft 44, with shafts 40 and 44 being bolted together at 46. Shaft 44 is journaled in the lower frame member 48 of frame 24 and is welded or otherwise secured at its upper end to a thin channel-shaped molding 50 which encircles the lower and forward edges of the window 26 and is fixedly secured thereto. The upper pivot shaft 52 for window 26 is journaled in the forward frame member 54 of frame 24 and is secured to a short channel-shaped member 56 which encircles molding 50 and is secured thereto. The shafts 52 and 44 are vertically aligned and define the vertical axis of swinging movement of the window 26. As can be seen from FIGURES 2, 6 and 7, the frame members 48 and 54 are each provided with an inwardly opening channel 58 which receives and seats a weather strip 60 to seal the lower and forward edges of the window 26 in the closed position thereof.

The rear frame member 62 of frame 24 is of generally H-shaped cross section as can be seen from FIGURES 4 and 5, and provides the division post channel between the vertically movable door window 27 and the window 26. The intermediate wall 63 of member 62 is bolted at 64 to member 54 and at 66 to a lug 68 of member 48 in order to fixedly secure member 62 to frame 24. Wall 63 is provided with a plurality of vertically spaced dimples 70, each of which is generally conically-shaped and opens inwardly of frame 24. Three such dimples are shown, although more or less may be provided as required. Adjacent two of the dimples 70, wall 63 is

lanced to provide angularly and generally forwardly and downwardly extending cam guides or tabs 72.

A locking channel member 74 is slidably received within the channel 75 of member 62 and is provided with a plurality of dimples 76 complementary in number to the dimples 70 and a plurality of cam guides or tabs 78 complementary in number to the tabs 72. Dimples 76 open in the same direction as the dimples 70 but are slightly smaller in size so as to be received within the latter in unlatched open or partially open position of the window 26, as shown in FIGURE 7. The tabs 78 and the tabs 72 slidably engage each other and move between a generally extended position with respect to each other when window 26 is in a latched and closed position, as shown in FIGURE 6, and a generally retracted position with respect to each other when window 26 is in an unlatched and open or partially open position, as shown in FIGURE 7. Channel member 74 is slotted at 80, adjacent the lower end thereof so as to move relative to lug 68. A compressible U-shaped weatherstrip 82 mounted in member 74 has the base wall thereof slotted at 84 opposite each of the openings in member 74 resulting from tabs 78. Slots 84 receive tabs 72 in the retracted position of these tabs relative to tabs 78, as shown in FIGURE 7.

Weatherstrip 82 receives the rear edge portion of window 26 in the closed and latched position thereof and is moved out of engagement with window 26 upon initial movement of the window to an open position.

A U-shaped bracket 85 is welded to the base of member 74 at the lower end thereof, and is pivotally secured at 86 to one end of a channel-shaped link 87. The other end of link 87 is pivoted at 88 to one leg of a bell crank lever 90 fulcrumed at 92 on flange 30. The other leg 94 of lever 90 is apertured and slidably receives a rod 96. The end of the rod is provided with an enlarged head 98 which engages leg 94 and shoulder 99 of lever 90 in the closed and latched position of window 26 as shown in FIGURE 6. Rod 96 is adjustably secured at 100 to one end of another rod 102. The other end of rod 102 is pivoted at 104 to a generally L-shaped lug 106 which is part of an annular spiral gear 108. As shown in FIGURE 6, gear 108 meshes with an input worm gear 110 which is driven by the handle 38. Referring now particularly to FIGURE 2, shaft 40 includes a shaft portion 112 of reduced diameter which is journaled in gear 108 and slotted at 114. A coil torsion spring 116 fits within a recess 118 of gear 108, with one end of the spring being received within slot 114, and the other end of the spring being received within a groove 120 in gear 108 in order to flexibly couple shaft 40 and gear 108. A clutch and bearing member 122 is pinned at 124 to shaft 40 and is biased into engagement with gear 108 by a Belleville spring washer 126. Member 122 locates gear 108 within unit 34 and also provides a friction brake for the shaft 40 in order to adjustably hold window 26 in any open position thereof.

The window 26 is shown in a latched and closed position in FIGURES 4 and 6, and in an unlatched and partially open position in FIGURES 5 and 7. If it is desired to move the window 26 to an open position, the handle 38 is rotated to rotate gear 110 and in turn rotate gear 108. As gear 108 rotates, it will swing lug 106 to shift rods 96 and 102 to the left as viewed in FIGURE 6. The engagement of the head 98 of the rod with shoulder 99 will swing the bell crank 90 clockwise, and shift link 87 upwardly. As the link 86 shifts upwardly, it will move the member 74 upwardly, and cause the dimples 76 to move upwardly and within the dimples 70 as the tabs 78 slide relative to the tabs 72 to cam member 74 simultaneously upwardly and rearwardly to its position shown in FIGURE 7 wherein member 74 is located entirely within member 62. This moves weatherstrip 82 out of engagement with the rear edge portion of window 26 to unlatch and unseal the window from member 62. Thus,

the locking channel member 74 is automatically moved out of engagement with the rearward edge of the window 26 upon initial opening movement of the window. Only a slight amount of rotational movement of gear 108 is required to move member 74 from its position of FIGURE 6 to its position of FIGURE 7. During this slight rotational movement of gear 108, window 26 remains in its closed position, since the windup of the spring 118 is not sufficient to couple the shaft 40 to gear 108 so that the shaft will rotate with the gear in a direct drive relationship. Thus, the spring 118 provides a lost motion connection between gear 108 and shaft 40 to permit member 74 to move within member 62 prior to any movement of the window 26 to open position.

As soon as member 74 moves within member 62, the rounded end of head 98 cams past shoulder 99 to permit further shifting movement of rods 96 and 102 relative to bell crank 90 as window 26 starts to move to open position.

Assuming now that the window 26 is in open position and handle 38 is operated to move the window to a closed position. When window 26 reaches a closed position, spring 118 will unwind as gear 108 rotates to shift rods 96 and 102 so that the enlarged head 98 of rod 96 will engage the leg 94 of bell crank 90 to swing the bell crank counter-clockwise as viewed in FIGURE 2 and in turn shift the link 87 downwardly. As the link 87 shifts downwardly, it will pull the member 74 downwardly to cam the dimples 76 out of the dimples 70 and into engagement with wall 63 of member 62 to thereby cam the member 74 simultaneously downwardly and forwardly and move the weatherstrip 82 into sealing engagement with the rear edge of the window 26 to lock the window to member 62 in its fully closed position. During the slight rotational movement of gear 108 after window 26 has reached its closed position, spring 118 will unwind so as to permit the window to remain substantially stationary while the member 74 is moved into engagement with the rear edge thereof. Since weatherstrip 60 is of the compressible type, it will permit some slight movement of the window 26 in its closed position in order to permit alignment of the rear edge of the window with member 74 and also to permit some movement of the gear 108 with the shaft 40, if necessary, in order to move member 74 to its position in sealing engagement with the rear edge of the window.

Thus, this invention provides a new and improved combined vehicle window regulator mechanism and latching means.

We claim:

1. In combination with a vehicle body having a window opening therein and a window mounted thereon for movement to open and closed positions, a window regulator mechanism and latching means comprising, operating means operatively connected to said window for moving said window between open and closed positions, a locking channel member, means mounting said member on said body for bodily movement into and out of engagement with an edge portion of said window, the edge portion of said window being received within the channel of said member in the closed position thereof, and being out of engagement with the channel of said member in the open position thereof, and means operatively interconnecting said member and said operating means for moving said member into engagement with said edge portion of said window upon movement of said window to the closed position thereof, and for moving said member out of engagement with said edge portion of said window prior to opening movement of said window.

2. In combination with a vehicle body having a window opening therein and a window mounted thereon for movement to open and closed positions, a window regulator mechanism and latching means comprising, operating means operatively connected to said window for moving said window between open and closed positions, a lock-

ing channel member, means mounting said member on said body for bodily movement in opposite directions relative thereto, cam means for camming said member into and out of engagement with an edge portion of said window upon movement of said member, the edge portion of said window being received within the channel of said member in the closed position thereof and being out of engagement with the channel of said member in the open position thereof, and means operatively interconnecting said member and said operating means for bodily moving said member in said opposite directions upon movement of said window between said open and closed positions.

3. In combination with a vehicle body having a window opening therein and a window mounted thereon for movement to open and closed positions, a window regulator mechanism and latching means comprising, operating means operatively connected to said window for moving said window between open and closed positions, a locking channel member, support means mounting said member on said body for movement with respect thereto within the plane of said opening, cam means camming said member between extended and retracted positions with respect to said support means and into and out of engagement with an edge portion of said window upon movement of said member, the edge portion of said window being received within the channel of said member in the closed position thereof and being out of engagement with the channel of said member in the open position thereof, and means operatively interconnecting said member and said operating means for bodily moving said member with respect to said support means upon movement of said window between open and closed positions.

4. In combination with a vehicle body having a window opening therein and a window mounted thereon for movement to open and closed positions, a window regulator mechanism and latching means comprising, operating means operatively connected to said window for mov-

ing said window to open and closed positions, a locking member, support means slidably mounting said member on said body, cam means for camming said member into and out of engagement with an edge portion of said window upon movement of said member, and means operatively interconnecting said member and said operating means for moving said member relative to said support means upon movement of said window between open and closed positions.

- 10 5. In combination with a vehicle body having a window opening therein and a window mounted thereon for movement to open and closed positions, a window regulator mechanism and latching means comprising, operating means operatively connected to said window for moving said window to open and closed positions, a locking channel member, a support channel on said body slidably receiving said member, cooperating cam means on said member and channel for camming said member into and out of engagement with an edge portion of said window upon movement of said member within said channel, the edge portion of said window being received within the channel of said member in the closed position thereof and being out of engagement with the channel of said member in the open position thereof, and means operatively interconnecting said member and said operating means for moving said member within said channel upon movement of said window between open and closed positions.
